UNITED STATES PATENT OFFICE.

THOMAS HENRY BECKS GAYNER, OF SOUTH MELBOURNE, VICTORIA, AUSTRALIA.

FABRIC FOR INFLATABLE ARTICLES.

982,049.

Specification of Letters Patent. Patented Jan. 17, 1911.

Application filed September 23, 1909. Serial No. 519,186.

To all whom it may concern:

Be it known that I, THOMAS HENRY BECKS GAYNER, a subject of the King of Great Britain, residing at 113 Neville street, South 5 Melbourne, in the State of Victoria, Commonwealth of Australia, cycle mechanic, have invented a Fabric for Inflatable Articles, of which the following is a specification.

- 10 The object of this invention is to enable inflatable articles which have heretofore been generally made of rubber or the like to be made up from textile material which is so treated as to render same not only air- 15 proof but capable of automatically sealing any punctures which may occur therein. This is achieved by treating textile material on one surface, *i. e.* that which will be the inner surface of the inflatable article, with 20 the commercial preparation known as Turkish bird-lime, as hereinafter more particularly described. Accordingly I take a suitable textile material such as canvas, water- 25 proof sheeting, or the like and apply thereto a coating or layer of Turkish bird-lime of a thickness of say from 1/16th to 3/8th of an inch, and in order to prevent sticking together, said coating is lightly covered or 30 dusted over with kapok, French chalk or other suitable non-adhesive substance. The textile material thus treated may be made up into various inflatable articles usually 35 made of rubber or the like, or certain articles such as air tubes or pneumatic tires may conveniently be first partially made up and then treated with the Turkish bird-lime by turning same inside out and after treatment re-turning same and joining the ends.

The invention is applicable to a large 40 variety of articles besides air-tubes, such for instance as pneumatic horse-collars and saddlery, air cushions, pneumatic seats for furniture, and is more especially of use as applied to inflatable articles which are liable 45 to puncture by reason of its automatic sealing property.

If desired the articles may be fitted with valves for the purpose of inflation, or this may be effected by the insertion through the 50 treated material of a light hollow needle

attached to an air or gas pump, inasmuch as on withdrawing same the puncture made by the needle is immediately sealed.

In some cases the textile material may be first furnished with a thin film of pure rubber on the inner side before the Turkish bird-lime is applied.

The preparation of Turkish bird-lime employed as aforesaid is made from the berries of a tree called "Mikssass", known 60 botanically as *Cordia myxa*, which grows in Syria, Queensland and other places. It is a commercial preparation already on the market.

Figure 1 is a sectional view of an article 65 formed in accordance with the invention, and Fig. 2 is a sectional view of a modified construction.

Referring to Fig. 1, in which an inflatable article, such as a cushion, is shown, A designates the textile material such as canvass, and C the coating of Turkish bird lime, upon which is lightly covered or dusted a layer, D, of non-adhesive substance. E designates a hollow needle provided with 70 perforations, which needle is adapted to be attached directly or indirectly to an air pump for inflating the article, and F designates a non-return air valve of the ordinary type, such as used with tires and the like, 75 which may be connected with an air pump, if desired, for the purpose of inflating the article.

The article shown in Fig. 2 is similar to the article shown in Fig. 1, with the exception that a thin film, B, of rubber is provided between the layer A and the layer C.

Throughout this specification the expression "textile material" shall be taken to include any equivalent or normally pervious 85 flexible material suitable for the purpose for which the inflatable article is intended.

Having now particularly described and ascertained the nature of my said invention and in what manner the same is to be performed, I declare that what I claim is;

1. As an article of manufacture, a fabric for inflatable articles comprising textile material having one of its surfaces coated with a layer of Turkish bird lime, said layer 100

2
being not less than one-sixteenth of an inch thick.

2. As an article of manufacture, a fabric for inflatable articles comprising textile material having one of its surfaces coated with Turkish bird lime and a non-adhesive substance covering said coating.

In testimony whereof I have hereunto set my hand in presence of two subscribing witnesses.

THOMAS HENRY BECKS GAYNER.
